D18,177

UNITED STATES PATENT OFFICE.

FRANCIS A. COFFIN, OF INDIANAPOLIS, INDIANA.

DESIGN FOR A WRITING-DESK.

SPECIFICATION forming part of Design No. 18,177, dated March 13, 1888.

Application filed December 15, 1887. Serial No. 258,035. Term of patent 7 years.

To all whom it may concern:

Be it known that I, FRANCIS A. COFFIN, of Indianapolis, county of Marion, and State of Indiana, have invented and produced a certain 5 new and original Design for Writing-Desks; and I do hereby declare that the following is a full, clear, and exact description thereof, reference being had to the accompanying engraving, which illustrates the same.

10 The engraving represents a perspective view of my newly-designed desk, and will be readily understood therefrom.

The desk has a table top resting upon a frame-work, one end supported by two turned legs, 15 the other by a pedestal which incloses a series of drawers. Beneath the top, and between the pedestal and legs of the desk, is a single long drawer. The top has a smooth flat surface, the edges extending over the frame-work and 20 ornamented with neat ogee molding. The front of the drawer projects when closed beyond the face of the frame and the edges are beveled. The handles of the drawers are flat with rounded ends and beveled edges. The 25 front corners of the pedestal on each side of the series of drawers are ornamented with flat pilaster molding with molded bases, as shown. Beneath the longer drawer are a couple of

small bracket-pieces ornamented with diagonal lines.

The leading features of my design consist in 30 molded edges of the table top, the pilasters upon the front corners of the pedestal with molded bases, the style of the handles, and edges of the drawers, with the small brackets 35 beneath the longer drawer.

I claim—

The design for desks, comprising a table-top with molded edges resting upon a frame-work supported at one end by turned legs, at the 40 other by a pedestal, its sides paneled, its front corners ornamented with flat molded pilasters having molded bases and inclosing a series of 45 drawers whose fronts have beveled edges and flat handles with rounded ends and beveled edges, and a longer drawer with similar edges and handles beneath the top, at the left of the pedestal, all the drawer fronts projecting beyond the front face of the table-frame, as herein shown and described.

In witness whereof I have hereunto set my hand this 2d day of November, 1887.

FRANCIS A. COFFIN.

Witnesses:

C. P. JACOBS,
E. B. GRIFFITH.
